UNITED STATES PATENT OFFICE.

JOHN F. CAVANAGH, OF MERIDEN, CONNECTICUT, ASSIGNOR TO CONNECTICUT TELEPHONE & ELECTRIC CO., INC., OF MERIDEN, CONNECTICUT, A CORPORATION OF CONNECTICUT.
TRANSFORMER-COIL FOR IGNITION, &c.

1,312,497.

Specification of Letters Patent.

Patented Aug. 5, 1919.

Application filed May 28, 1918. Serial No. 237,160.

To all whom it may concern:

Be it known that I, JOHN F. CAVANAGH, a citizen of the United States of America, residing at Meriden, Connecticut, have invented a new and useful Transformer-Coil for Ignition, &c., of which the following is a specification.

My present invention relates to spark coils for electric ignition systems and the general objects of the invention are to improve such coils both from an electrical and a structural standpoint.

Special objects of the invention are to gain increased electrical efficiency and thereby enable a reduction in size of the coil and quantity of materials used, to intensify the ignition spark and to reduce sparking at the breaker points of the primary circuit and to provide a coil which will be relatively small, compact and well protected.

These objects I have accomplished by constructing the coil with the secondary about the core and the primary about the secondary and by placing the condenser about the primary, the whole being incased in a magnetic shell to the ends of which insulating heads or end caps are applied forming supports for the terminals. Preferably the high tension terminal is mounted on one of the insulating end caps and all the other terminals are mounted on the other insulating end cap.

Other features of the invention will appear as the specification proceeds.

In the accompanying drawing I have illustrated the invention embodied in a practical commercial form, this with the understanding however, that such disclosure is merely illustrative of the invention and that changes and modifications may be made without departure from the true spirit and scope of the invention.

In said drawing:—

Figure 1, is a longitudinal sectional view of the coil.

Fig. 2, is a broken side elevation thereof.

Fig. 3, is a more or less diagrammatic representation of the invention as applied to a typical battery distributor system.

Considering the drawing now in detail; 5 designates the magnetic core which may be constructed of iron wire or other material, as customary. 6 designates the secondary winding applied in this case directly to the 55 core and 7 the primary winding applied to

and surrounding the secondary, suitable insulating layers 8 and 9 being usually interposed between the core and the secondary winding and between the two windings respectively.

10 designates the condenser which in accordance with this invention is placed outside and surrounding the primary winding, said condenser being usually made up of alternating layers of foil and a suitable dielectric and the whole coiled about or sleeved over the primary.

11 designates the outer magnetic shell or casing which incloses the condenser and windings and serves both structurally as a 70 housing and magnetically as a part of the magnetic circuit.

12 and 13 designate the end heads or caps made of insulating material and applied to the ends of the magnetic shell so as to form 75 a complete inclosure for the various parts. These end caps are secured in place in the present disclosure by a securing screw 14 extending through the core and having nuts 15 engaged with the threaded extended ends 80 thereof for forcing the end caps into close fitting engagement with the shell.

In accordance with my invention all the low tension terminals are mounted on the one end cap 12 and the high tension terminal 85 is mounted on the opposite end cap and therefore comparatively far removed from the low tension terminals. In the illustration 16 and 17 designate the terminals for the primary winding and 18 a terminal in 90 the primary circuit, all mounted on the end cap 12. 19 designates the secondary or high tension terminal mounted within a tubular housing or extension 20 on the opposite end cap 13, said housing being constructed to receive 95 the end of the high tension cable.

A typical circuit arrangement for the coil is illustrated in Fig. 3, wherein the battery 21 is shown connected by a lead 22 with the primary terminal 16. The other primary 100 terminal 17 is connected by a lead 23 with the breaker arm of the circuit interrupter 24, the other side of the circuit interrupter being connected by a lead 25 with the terminal 18. From this terminal 18 a connection is made as indicated at 26, with the magnetic shell, which serves as a ground, said shell being suitably grounded on the frame of the car or other structure as by means of its supporting bracket 27. This 110

forms the primary circuit, it being noted that the opposite side of the battery is grounded as indicated at 28. The secondary coil is grounded at one end as by means of 5 the connections 29—26 and at its opposite end is connected as by means of a high tension cable 30 with the arm of the distributor 31, which is connected in the usual way with the sparking appliances. The condenser is 10 connected across the breaker points as by means of connections 32—26 and 33.

In this invention the secondary is placed close to the core and hence in the strongest 15 part of the magnetic field, while the primary is disposed in a comparatively weak portion of the magnetic field. This tends to produce a minimum counter E. M. F. in the primary resulting in a minimum amount of sparking 20 at the breaker points while the location of the secondary in the strongest part of the magnetic field causes it to be energized to a maximum degree. In other words, the highest electrical efficiency is obtained from 25 both the secondary and the primary, and this results in the production of a very hot and efficient ignition spark.

Also, in my construction, the condenser is far removed from the influence of the secondary winding and is at a point where the 30 leads from the secondary, primary and condenser are common in that there is practically no difference in potential. Another

important point of advantage is that by the location of the condenser adjacent the shell, 35 said condenser is disposed in the coolest part of the construction, resulting in the condenser being kept relatively cool and without the variation in capacity which arises from heating of a condenser.

Structurally, the invention possesses many 40 advantages particularly in the ease of assemblage, the small size and compactness of the coil and the fact that it is weather-proof with all parts thoroughly protected.

I claim:

1. In a spark coil, the combination of a 45 step-up secondary winding, a primary winding surrounding said secondary winding, and a condenser surrounding said primary winding, and thereby relatively far removed from the influence of the secondary.
2. In a combination like that set forth in claim 1, a magnetic shell disposed outside said primary winding and providing a return magnetic path. 55
3. In a spark coil, primary and secondary windings, a magnetic shell inclosing the same, end caps of insulating material applied to said magnetic shell, low tension terminals on one of said end caps, and a high tension terminal on the opposite end cap and removed from the low tension terminals. 60

JOHN F. CAVANAGH.
